ART OF CRACKING HYDROCARBONS

Orin G. Kaasa, Munster, Ind., assignor to Sinclair Refining Company, New York, N. Y., a corporation of Maine

Application November 14, 1932, Serial No. 642,496

2 Claims. (Cl. 196—61)

My invention relates to improvements in the cracking of petroleum stocks containing a substantial proportion of gasoline at high cracking temperatures for the production of gasoline fractions of improved anti-knock value. In referring to stocks containing a substantial proportion of gasoline, I refer to stocks of which more than 40% boils off up to 420° F. at atmospheric pressure and intend to include stocks of which as much as 90% or more boils off at 420° F. under atmospheric pressure. In referring to high cracking temperatures, I refer to cracking temperatures upwards of 890° F. Operations of this general character are sometimes designated "reforming" operations.

By cracking gasoline fractions, or stocks containing substantial proportions of gasoline, at high cracking temperatures, the gasoline content of the stock as well as higher boiling components are cracked with consequent formation, under appropriate conditions which are well known, of gasoline fractions of anti-knock value improved with respect to that of the original gasoline content of the stock. The cracking temperatures useful for this purpose are so high that, particularly with respect to such stocks, the stock is usually completely vaporized except for particles of gum constituents, tar constituents or very high boiling constituents of the stock which remain unvaporized as a fog or mist in the operation. Under appropriate conditions, such normally small proportions of unvaporized material can be maintained in suspension in a rapidly flowing stream of vapors and thus carried through and discharged from the heating involved in such operations, but prior to that point in the operation at which the change in phase from the liquid state in which the stock is supplied to the heating to the vapor state in which it is discharged from the heating ceases any segregation of such gum constituents, tar constituents or very high boiling constituents tends to involve overheating of the conduit, for example, in which the heating is effected and any overheating of this portion of the conduit tends to involve such segregation and these two tendencies become mutually cumulative. Even though the hazards of apparatus failure be ignored, these tendencies involve limitations of the capacity of the apparatus in which such operations are carried out. If the effect of these tendencies is ignored, except as it requires termination of the operation for cleaning of the apparatus, the proportion of time over which the apparatus can be usefully operated is decreased and if the apparatus is oper-

ated at a lower heating rate either to reduce the rate of segregation of such constituents or to reduce the effect of such segregation as occurs, the capacity of the apparatus is correspondingly decreased.

I have found, however, that by limiting the rate of heat transfer to the stock from a point in advance of that at which substantial vaporization begins to the point at which the phase change substantially ceases as compared to the rate of heat transfer to the stock beyond the point at which the phase change substantially ceases, and more particularly immediately beyond this point, these tendencies can be eliminated, at least in a substantial measure, without substantial prejudice to the capacity of the apparatus in which the operation is conducted.

According to my invention, the stock to be cracked is supplied to a heating conduit substantially in liquid phase, it is heated to a high cracking temperature therein while flowing therethrough as a stream, and it is discharged therefrom substantially in vapor phase, and a lower rate of heat transfer per unit of area of the heating conduit is maintained from a point in advance of that at which substantial vaporization begins to the point at which the phase change, from the liquid phase in which it is supplied to the heating conduit to the state in which it is discharged therefrom, substantially ceases than immediately beyond the last mentioned point.

My invention is of special value in conjunction with operations, or that part of operations, in which the heat supplied to the oil during the heating is transferred principally as radiant energy. Realization of a full measure of capacity available in apparatus of this type usually involves very high rates of heat transfer. In operations conducted in such apparatus, the tendencies toward overheating and segregation to which I have referred are particularly objectionable and the elimination of these tendencies affords an unusual measure of advantage. In carrying out my invention in such apparatus, the heating conduit is shielded from the source of radiant energy from a point in advance of that at which substantial vaporization begins to the point at which the phase change substantially ceases, a differential between the rates of heat transfer in advance of the last-mentioned point and beyond that point thus being established.

My invention will be further described in connection with the accompanying drawing which illustrates, diagrammatically and conventionally,

two of the several forms of apparatus adapted for the practice of my invention. In the accompanying drawing, Fig. 1 represents, in elevation and in section and with parts broken away, a 5 heating furnace within which a heating conduit is arranged, Fig. 2 is a detail, in section, of a heating tube, shield and shield support, and Fig. 3 represents in elevation and in section and with parts broken away, another form of heating furnace 10 within which a heating conduit is arranged.

Referring to Fig. 1, the heating conduit consists of a number of serially connected heating tubes to which stock is supplied at 5 and from which stock is discharged at 6. The flow of the 15 stock, and its direction, is indicated in the drawing by the broken lines bearing arrows drawn through the heating tubes which appear in section. The stock first passes through a bank of so-called "convection" tubes in the flue 7 then 20 through a bank of so-called "radiant" tubes on the inner wall of the chamber 8, then through a divided bank of "radiant" tubes on the outer wall of the chamber 8 then through a bank of "radiant" tubes on the roof of the furnace structure 25 and then, successively, through three banks of "convection" tubes in the flue 7. Shields 9 are arranged over that part of the external surface of the heating tubes in the bank on the inner wall and on the lower part of the bank 30 on the outer wall of the chamber 8 which more directly faces the locus of radiation. The combustion of fuel, supplied through gas burners 10 for example, provides a source of heat largely available as radiant energy within the chamber 35 8. The products of combustion flow from the chamber 8 through the flue 7, in which the several banks of "convection" tubes are arranged, to a fan 11. Part of the waste heating gases discharged by the fan 11 may, with advantage, 40 be recirculated through the chamber 8 with the fresh products of combustion, and more particularly over the walls of the chamber 8 on which the heating tubes are arranged, to assist in protection of the heating tubes. Such recirculated 45 heating gases are returned through flue 12. Heating gases not recirculated through flue 12 are discharged through flue 13. The stock to be cracked, supplied in liquid phase, is progressively heated as it flows through the first bank of tubes 50 in the flue 7 and then through the bank of tubes on the inner wall of chamber 8 and the lower part of the bank of tubes on the outer wall of the chamber 8 until the change in phase from the liquid state in which it is supplied to the state 55 in which it is discharged is substantially completed, that is until phase change ceases. The operation is controlled, by regulation of the rate of supply of the stock and the rate of firing for example, so that this point at which change in 60 phase ceases is reached just before the stream of stock passes from the last shielded tube in the lower part of the bank on the outer wall of chamber 8 into the first unshielded tube in this bank. It will be apparent that the lowermost 65 bank of heating tubes in the flue 7 is effectively shielded from the locus of radiation in the chamber 8 by the inner wall of this chamber, so that the conduit in which the heating is effected is shielded from a point in advance of that at 70 which substantial vaporization begins to the point at which the phase change substantially ceases.

Referring to Fig. 3, the heating conduit consists of a number of serially connected heating tubes to which stock is supplied at 15 and from which stock is discharged at 16. The stock first

passes through a bank of tubes on the roof of the furnace structure and then through a bank of tubes arranged within the chamber 18 above the muffles 14. The combustion of fuel, supplied through gas burners 20 for example, is effected within the muffles 14. The products of combustion discharged from the muffles into duct 17 pass through the chamber 18 to the stack flue 21. Heat is transferred to the heating tubes from the heating gases passing through the chamber 10 18 and also, as radiant energy, through the upper walls of the muffles 14, these walls being constructed of material, silicon carbide for example, adapted to permit the transmission of radiant heat. Shields 19 are arranged over that part of 15 the external surface of the heating tubes in the bank on the roof of the furnace structure through which the stock first passes facing the cover of the duct 17 through which the products of combustion discharged from the muffles 14 enter the 20 chamber 18. The stock to be cracked, supplied in liquid phase, is progressively heated as it flows through the bank of tubes on the roof of the furnace structure until the change in phase from the liquid state in which it is supplied to the 25 state in which it is discharged is substantially completed, that is until phase change ceases. The operation is controlled, by regulation of the rate of supply of the stock and the rate of firing for example, so that this point at which change in 30 phase ceases is reached just before the stream of stock passes from the last shielded tube in the bank on the roof of the furnace structure into the first unshielded tube in this bank.

The precise form of shields and shield supports used is not vital to my invention. A detail of one useful form is illustrated in Fig. 2. In this form the shield 22 of steel or an appropriate alloy, generally semicircular in section, is welded at intervals to U-bolts 23 by which it is clamped 40 to the heating tube 24 to which it is applied. A construction of this type, facilitating the placing and removing of the shields, is advantageous in that it permits adjustment of the apparatus to meet the requirements of varying operations. 45

In carrying out my invention, in the apparatus illustrated for example, the conduit in which the stock is heated to a high cracking temperature is shielded from a point in advance of that at which substantial vaporization begins to the 50 point at which the phase change substantially ceases to maintain a rate of heat transfer, through this part of the conduit, substantially lower than that maintained immediately beyond the point at which the phase change ceases, but 55 this rate of heat transfer, through the shielded part of the heating conduit, is nevertheless, sufficient to effect the phase change involved within the shielded part of the conduit. In referring to the point at which phase change ceases, it will 60 be apparent that I mean to say that no substantial vaporization takes place beyond this point and not that vaporization is complete at this point. The metal temperatures encountered along the conduit in which the stock is heated in 65 carrying out my invention afford one measure of the advantage of my invention. If two operations, corresponding except in that in the second no differential between the heat transfer rates in advance of and immediately beyond the 70 point at which phase change ceases is maintained, are compared by this standard, it will usually be found that much higher metal temperatures are encountered in advance of this point in the second than in the first. That is 75

to say, for the same capacity metal temperatures are reduced. The converse is also true, that the capacity can be increased without increasing the maximum metal temperatures encountered.

5 I claim:

1. In cracking petroleum stocks containing a substantial proportion of gasoline for the production of gasoline fractions of improved anti-knock value, the improvement which comprises supplying a stock of which more than 40% boils off up to 420° F. at atmospheric pressure to a heating conduit substantially in liquid phase, heating the stock to a high cracking temperature in the heating conduit while flowing therethrough as a stream, discharging the heated stock from the heating conduit substantially in vapor phase, maintaining a rate of heat transfer per unit of area of a portion of said conduit extending beyond the point at which the phase change substantially ceases such that overheating of said portion of said conduit will not occur but such that if this same rate of heat transfer were maintained throughout the entire conduit overheating would occur in a portion of the conduit in which takes place a part of the phase change, and maintaining a rate of heat transfer per unit of area of said conduit lower than the rate of heat transfer first mentioned from a point in advance of that at which substantial vaporization begins to a point at which there has occurred an amount of vaporization such that immediately beyond this point no further substantial over-

heating of the heating conduit will occur with the rate of heat transfer first mentioned.

2. In cracking petroleum stocks containing a substantial proportion of gasoline for the production of gasoline fractions of improved anti-knock 5 value, the improvement which comprises supplying a stock of which more than 40% boils off up to 420° F. at atmospheric pressure to a heating conduit substantially in the liquid phase, heating the stock to a high cracking temperature 10 in the heating conduit while flowing therethrough as a stream by heat transferred principally as radiant energy, discharging the heated stock from the heating conduit substantially in the vapor phase, maintaining a rate of heat 15 transfer per unit of area of a portion of said conduit extending beyond the point at which the phase change substantially ceases such that overheating of said portion of said conduit will not occur in the absence of shields but such that 20 overheating would occur in a portion of said conduit in which takes place a part of the phase change if this same rate of heat transfer were maintained throughout the entire conduit, and shielding said conduit from the source of said 25 radiant energy from a point in advance of that at which substantial vaporization begins to the point at which there has occurred an amount of vaporization such that immediately beyond this point no further substantial overheating of the 30 heating conduit will occur with the rate of heat transfer first mentioned.
